(57) CLAIM

The ornamental design for scrub pants as shown and described.

DESCRIPTION

FIG. 1 is a front perspective view of scrub pants showing the claimed design;

FIG. 2 is a front elevation view thereof;

FIG. 3 is a rear elevation view thereof;

FIG. 4 is a left side elevation view thereof;

FIG. 5 is a right side elevation view thereof; and,
FIG. 6 is a partial cross-sectional view thereof taken along line 6-6 in FIG. 4.

The dashed broken lines show a stitching pattern that forms part of the claimed design.

The dot-dash broken lines in the figures show portions of the scrub pants that form no part of the claimed design.

1 Claim, 6 Drawing Sheets
